BEET TOPPER

Lloyd Botimer, Vassar, Mich.

Application March 7, 1949, Serial No. 80,068

10 Claims. (Cl. 56—121.46)

1

This invention relates generally to beet harvesting apparatus and refers more particularly to improvements in beet harvesting apparatus of the general type disclosed in my copending application Serial No. 736,886, filed March 24, 1947, now Patent No. 2,509,757.

It is one of the objects of this invention to simplify the construction of the apparatus and provide a more compact assembly capable of being readily attached to farm type tractors without appreciably modifying the construction of the latter.

It is another object of this invention to provide beet topping mechanism having a cutter rotatable about an axis inclined at a predetermined angle with respect to the vertical and movable generally vertically while maintaining the predetermined angular relationship aforesaid of the cutter axis. This arrangement enables the use of a cutter in the form of a large diameter disc and permits locating the disc in proper cutting relation to a preceding beet without interference from the next adjacent succeeding beet.

It is still another object of this invention to pivotally connect the cutter supporting means to a suitable frame by a parallelogram arrangement of linkage operated by a follower positioned to engage the beets in advance of the cutter and raise the cutter to the proper elevation for severing the top off the beet previously contacted by the follower. Thus the elevation of the cutter is determined by the height of the beet immediately preceding the cutter and only the very top of the beet is severed regardless of the extent to which the beet projects above the ground.

It is a further object of this invention to strip the foliage off the beets prior to engagement of the follower with the beet tops, and thereby eliminate to a great extent any effect the foliage may have on vertically positioning the cutter with respect to the beets. The above may be accomplished by a disc supported in advance of the follower for rotation in a plane substantially normal to the path of travel of the apparatus along a beet row and having a flexible peripheral portion engageable with the beet tops. In use the peripheral portion of the disc whips across the beet tops, and the resulting friction strips or removes the major portion of the foliage from the beet tops.

It is a still further object of this invention to provide improved releasable latch mechanism for holding the cutter in its elevated cutting

2

position during the cutting operation and for releasing the cutter subsequent to the cutting operation.

The foregoing as well as other objects will be made more apparent as this description proceeds, especially when considered in connection with the accompanying drawings, wherein:

Figure 1 is a side elevational view with parts broken away of a beet harvesting apparatus showing the same applied to a tractor;

Figure 2 is a side elevational view with parts broken away similar to Figure 1 showing the parts of the beet harvesting apparatus in a different position;

Figure 3 is an enlarged fragmentary side elevational view of the beet harvesting apparatus showing the same in still another position;

Figure 4 is a sectional side elevational view of the beet harvesting apparatus having a number of parts broken away for the sake of clearness;

Figure 5 is a plan view of the beet harvesting apparatus;

Figures 6, 7, 8, 9, 10, 11 and 12 are respectively sectional views taken on the lines 6—6, 7—7, 8—8, 9—9, 10—10, 11—11 and 12—12 of Figure 4;

Figure 13 is a sectional view taken on the line 13—13 of Figure 3;

Figure 14 is an enlarged fragmentary front elevational view of a part of the beet harvesting apparatus;

Figure 15 is a cross sectional view taken on the line 15—15 of Figure 4; and

Figure 16 is an enlarged fragmentary elevational view of another part of the apparatus.

The beet harvesting apparatus forming the subject matter of this invention is designated in the several figures of the drawings by the numeral 20, and is in the form of an assembly attachable as a unit to a tractor designated generally in the drawings by the numeral 21. The tractor 21 may be of any farm type, and the harvesting apparatus 20 is mounted at one side of the tractor between the front and rear axles of the latter.

The harvesting apparatus 20 has a rectangularly shaped frame 22 which extends longitudinally of the tractor and forms a unitary support for the various instrumentalities of the apparatus to be presently described. In detail the rear end 23 of the frame is offset downwardly, and is adapted to be suitably clamped to the underside of the rear axle of the tractor. The front end of the frame 22 is welded or otherwise

secured to the upper end of a vertical plate 24 having a bracket 25 secured thereto adjacent the lower end thereof in a position to be attached to the framework of the tractor.

Suitably supported on the frame 22 between the laterally spaced side sills 26 is a beet topping mechanism 27. This mechanism comprises a cutter 28 in the form of a disc having the central portion secured to a plate 29 by a cap 30 and suitable fastener elements 31. The plate 29 is positioned at the top side of the cutter disc 28, and the cap 30 is located at the bottom side where it forms a protective shield for the cutter disc. The peripheral portion of the cutter disc 28 flares in a general upward direction to impart a 15 dish-shaped cross section to the cutter disc, and the outer edge is ground or otherwise formed to provide a cutting edge 32, shown in Figure 4 of the drawings.

It will also be noted from Figure 4 of the drawings that the plate 29 is recessed at its center for receiving the lower end of a shaft 33, and is secured to the shaft by a stud 34. The shaft 33 is surrounded by a tubular shaft 35, and is journalled in the lower end of the tubular shaft by a suitable bearing 36. The upper end of the shaft 33 is journalled in a bearing 37 and projects upwardly beyond the bearing 37 for attachment to a beveled pinion 38.

The tubular shaft 35 is journalled in bearings 39 and 39' spaced from each other axially of the shaft and respectively secured to opposite ends of a tubular housing 40. The upper end of the tubular shaft 35 projects beyond the top bearing 39', and is secured to a cap 41, which in turn, is either integral with or secured to the lower end of the bearing 37 for the upper end of the shaft 33. It follows from the foregoing that the tubular shaft 35 forms a support for the cutter shaft 33, and is capable of rotation relative to the latter shaft.

As also shown in Figure 4 of the drawings, the tubular shaft 35 operates a casting element 42 positioned immediately above the cutter disc 28 for throwing the severed beet tops to one side of the row subsequent to the cutting operation. The casting element 42 comprises a sleeve 43 and an arm 44 extending radially outwardly from the sleeve 43. The sleeve 43 is suitably secured to the lower end of the tubular shaft 35 and the arm 44 is connected to the sleeve by a scraper 45. The scraper 45 is bent downwardly at the outer end to assume a position immediately adjacent the top surface of the cutter disc 28 and the leading edge 46 of the scraper is beveled as shown in Figure 9 of the drawings to remove any dirt or foreign matter that may become lodged on the cutter disc.

The shafts 33 and 35 are supported on the frame 22 with their common axis inclined at a predetermined angle with respect to the vertical. The angle of inclination is determined so that the low side of the disc 28 faces the front end of the frame in a position to engage the uncut beet immediately in advance of the cutter disc 28 and so that the rear side of the disc is elevated sufficiently to clear the beet just cut or topped by the disc 28. For supporting the shafts in the above position the means shown in Figure 3 of the drawings is provided. In detail a pair of bars 47 are secured to opposite sides of the tubular housing 40 in parallel relation to the shafts 33 and 35. Also as shown in Figure 6 of the drawings, a pair of vertically extending plates 48 are respectively secured to the frame sills 26 and are connected at

the upper ends by a pin 49. The upper ends of the bars 47 are connected by a similar pin 50 and the latter also serves as a pivotal support for the rear ends of a pair of laterally spaced rearwardly extending links or arms 51. The links 51 are pivotally supported adjacent their front ends on a pin 49 and a counterbalancing spring 52 is connected at its upper end to the front ends of the links beyond the pin 49. The lower end of the spring 52 is suitably anchored on the plates 48 and thereby tends to swing the beet topping mechanism 27 upwardly.

The lower ends of the bars 47 are respectively pivotally connected to the rear ends of a pair of links or arms 53 by pins 54 which also serve to connect the adjacent ends of the bars to opposite sides of the tubular housing 40. The front ends of the links 53 are pivoted on a pin 55 which extends between the bottom portions of the plates 48 in the manner shown in Figure 6 of the drawings. The above construction is such that the distance between the pins 49 and 55 approximates the distance between the pins 50 and 54. Also the distance between the pins 49 and 50 is substantially the same as the distance between the pins 54 and 55. Thus the connection between the supporting housing 40 and frame 22 is accomplished by a parallelogram arrangement of linkage with the result that vertical displacement of the beet topping mechanism 27 is obtainable while maintaining the predetermined angle of inclination of the shafts 33 and 35 previously described.

The beet topping mechanism 27 is shown in Figure 3 of the drawings in its lowermost position, and is elevated to properly position the cutter disc 28 relative to the next beet to be cut by a follower device 56. This device embodies extensions 57 respectively projecting forwardly from the lower ends of the bars 47 and connected at the front ends by a rod 58. A plurality of bars 59 are secured to the rod 58 in spaced relationship longitudinally of the rod, and project generally downwardly and rearwardly from the rod 58, as shown in Figures 1 to 4 inclusive of the drawings. The rear ends of the bars 59 are connected to another rod 60 which in turn serves to connect the lower ends of a pair of links 61 having the upper ends respectively pivotally connected to the rear ends of a pair of links or arms 62 by a pin 63. The links 62 respectively extend forwardly along opposite sides of the housing 40 at the inner sides of the arms 47, and the front ends of the links are respectively pivoted to the lower ends of the plates 48 by a pin 64.

The bars 59 are supported in such a manner that when the apparatus 20 is in use, these bars contact the beet tops in advance of the cutter disc 28. The bars 59 are inclined in a downward direction from the lower ends of the extensions 57 and have a sliding contact with the beet tops in the manner shown in Figure 4 of the drawings. Attention is directed to the fact that the lower ends of the links 61 are provided with a series of vertically spaced openings 65 for selectively receiving the pin 60, and the rear ends of the links 62 are formed with longitudinally spaced openings 66 for selectively receiving the pin 63. This construction provides an adjustment enabling the elevation of the follower or bars 59 to be varied with respect to the elevation of the cutter disc 28.

Referring again to Figure 4 of the drawings, it will be noted that as the apparatus 20 is advanced

by the tractor 21 along a beet row, the follower or bars 59 successively engage the beets in advance of the cutter disc 28. As a result the bars 59 are swung upwardly about the axis of the rod 58, and impart an upward movement to the links 61. This upward movement of the links 61 is transmitted to the rear ends of the links 62, and the extent of swinging movement of the links 62 about the axis of the pin 64 depends upon the height of the beet engaged by the bars 59. In accordance with this invention the cutter disc 28 is raised a corresponding distance and is thereby located at the proper elevation to merely cut the top off the adjacent beet.

For accomplishing the above result, the links 62 are connected intermediate the ends by a pin 67, and the latter extends through enlarged openings 68 formed in laterally spaced plates 69 and provides a lost motion pivotal connection. The distance between the pin 64 and the pin 67 is also the same as the distance between the pins 49 and 50. As shown in Figure 12 of the drawings the plates 69 extend rearwardly from the housing, and are secured in lateral spaced relationship at the front ends by spacers 10 which are welded or otherwise secured to an arcuate plate 71. The plate 71 is shown in Figure 4 of the drawings as extending lengthwise of the housing 40 between the bearings 39 and 39', and is secured to the rear side of the housing. Thus upward movement of the follower 56 is transmitted by the pin 67 and plates 69 to the supporting housing 40 for elevating the cutter disc 28 a distance depending upon the height of the beet engaged by the follower.

Provision is also made herein for swinging the cutter disc and follower to a raised or inoperative position shown in Figure 1 of the drawings. As shown in Figures 3, 5 and 13 a pair of laterally spaced links 72 are secured at their front ends on a pin 73 extending between and supported on the plates 48. The rear ends of the links are normally engaged with a seat 74 in the form of a bar extending transversely of the frame 22 and secured to the sills 26. Also the rear end portions of the links 72 are connected by a pivot pin 75 having a part intermediate the links 72 forming an anchor for the lower end of a vertical rod 76. The upper end of the rod 76 is slidably supported by a pivot pin 77 having an opening intermediate the ends for freely receiving the rod 76 and having the opposite ends respectively pivotally connected to the links 51 adjacent the pin 59. A shoulder 78 is secured to or formed on the rod below the pin 77 in a position to abut the bottom side of the pin 77 when the beet topping mechanism 20 is in its lowermost position shown in Figure 3 of the drawings.

Referring now to Figures 3, 4 and 6 of the drawings, it will be noted that a vertical link 79 is secured at its upper end on the pin 73. The lower end of the link 79 is connected to the front end of a link 80 having its rear end suitably connected to the hydraulic lifting arms (not shown) forming a standard part of orthodox tractors. It follows from the above that the application of a pulling force in a rearward direction on the link 80 operates the link 79 to swing the rear ends of the links 72 upwardly from the position thereof shown in Figure 3 of the drawings. Upward movement of the rear ends of the links 72 imparts a corresponding movement to the vertical rod 76, and the shoulder 78 on the rod transmits this upward movement to the rear ends of the links 51. Since the rear ends of the

links 51 are connected to the housing 40 through the bars 47, it follows that the cutter disc 28 and follower are elevated to the inoperative position shown in Figure 1 of the drawings.

The shaft 33 to which the cutter disc 28 is secured is driven by the power take-off shaft 80 forming a part of the tractor 21 and connected to the tractor engine in the usual manner. As shown in Figures 1 and 2 of the drawings, a pulley 81 is secured to the shaft 80 and is connected to a pulley 82 by a belt 83. The pulley 82 is secured to the rear end of a shaft 84 shown in Figure 5 as extending forwardly along one side of the frame 22 and journalled in a housing 85 which is secured to the adjacent sill 26 of the frame. A beveled pinion 86 is secured to the shaft 84 at the front end of the housing 85, and meshes with a beveled pinion 87 secured to the adjacent end of a shaft 88. The shaft 88 extends transversely of the frame 22 at the front end of the latter, and is journalled in bearings 89 respectively secured to the plates 48, as shown in Figures 5 and 6 of the drawings.

The shaft 88 is operatively connected to the pinion 38 at the upper end of the shaft 33 by the following mechanism which is shown in Figures 4 and 5 of the drawings. In detail a sprocket 90 is secured to the shaft 88, and is connected to a sprocket 91 by a chain 92. The sprocket 91 extends between the upper end portions of the bars 47, and is suitably journalled on a shaft 93. Mounted on the shaft 93 and secured to the sprocket 91 is a beveled pinion 94, and this pinion meshes with the beveled pinion 38 secured to the upper end of the shaft 33. Thus it will be noted that the shaft 33 is driven from the power take-off shaft 80, and since the cutter disc 28 is secured to the lower end of the shaft 33, it follows that this disc is rotated as a unit with the shaft 33. It will be noted that the distance between the axis of the shaft 88 and the axis of the shaft 93 approximates the distance between the pivot pins 49 and 50. The purpose of this arrangement is to enable vertical displacement of the beet topping mechanism 21 by the parallelogram arrangement of linkage without disturbing the driving connection between the power take-off shaft 80 and the cutter disc 28.

As stated above the casting element 42 is rotatable about the axis of rotation of the cutter disc 28 to throw the severed beet tops to one side of the row being traversed by the apparatus. In accordance with this invention the casting element 42 is periodically rotated in timed relation to the operation of the cutting disc 28. More particularly the casting element is rotated immediately following the operation of the cutting disc 28 to cut the top portion off a beet, so that this top portion is cast to one side by the arm 44 of the element 42. As shown in Figures 4 and 15 of the drawings, the shaft 33 is connected to the tubular shaft 35 for rotating the casting element 42 by a suitable clutch 95. This clutch embodies a plate 96 secured to the shaft 33 between the pinion 38 and the bearing 37. Also the clutch includes a pawl or latch member 97 pivotally supported by a pin 98 on the plate 41 to one side of the tube 35 for rocking movement about an axis parallel to the axis of rotation of the shaft 35. The pawl 97 has an arm 99 which projects outwardly for selective engagement with a plurality of pins 100 extending downwardly from the plate 96 and spaced circumferentially from one another around the periphery of the plate. The pawl 97 has an additional arm 101 which ex-

tends outwardly in angular relationship to the arm 99, and is normally urged into engagement with a stop pin 102 on the plate 41 by a spring 103. This position of the pawl is indicated by the dotted lines in Figure 15 of the drawings, and when in this position, the outer end of the arm 99 is in the path of travel of the pins 100. Thus as the plate 96 rotates with the shaft 33 in the direction of the arrow in Figure 15 of the drawings, one of the pins 100 contacts the outer end of the arm 99, and imparts a rotative movement to the shaft 35. On the other hand, when the pawl 97 is in the full line position thereof shown in Figure 15 of the drawings, the arm 99 rests against a stop pin 104 projecting upwardly from the plate 41 in a position to locate the arm 99 out of the path of travel of the pins 100. Thus in the full line or inoperative position of the pawl, the plate or shaft 35 is disconnected from the clutch plate 96 and rotation of the casting element 42 is discontinued.

As will be presently described the pawl 97 is held against the action of the spring 103 in its inoperative or full line position shown in Figure 15 of the drawings by the front end of a rod 105. This rod remains in blocking position with the arm 101 of the pawl 97 until completion of the cutting operation by the disc 28. Immediately after the cutting operation the rod 105 is shifted out of blocking engagement with the pawl, and the latter is operated by the spring 103 to impart rotation to the casting element 42. In order to avoid reverse rotation of the casting element 42 upon completion of its operation, suitable anti-back lash mechanism 106 is provided. This mechanism is shown in Figures 4 and 11 of the drawings, and comprises a cam 107 and a spring pressed plunger 108. The cam 107 is formed on a tube surrounding the shaft 35 between the bearings 39 and 39' and secured to the shaft 35 by screws 109. The plunger 106 is supported for sliding movement toward and away from the cam in a housing 110 secured to the arcuate plate 71. A spring 111 is located within the housing 110 and urges the plunger 106 against the cam 107. The cam 107 has an abrupt shoulder 112 positioned to engage the inner end of the plunger and prevent any tendency for the shaft 35 to reverse its direction of rotation upon being disconnected from the driving mechanism.

Also in accordance with the present invention the cutting disc is held in its elevated position throughout the cutting operation, and this is accomplished by releasable latch mechanism 113 shown in Figures 3 and 4 of the drawings. The releasable latch mechanism comprises a pair of laterally spaced plates 114 extending between the plates 69 and respectively having upstanding ears 115 intermediate the ends. As shown in Figure 7 of the drawings the plates 69 are respectively formed with similar ears 116, and the latter are pivotally connected to the ears 115 by a pin 117 so that the plates 114 are actually pivoted to the plates 69 for swinging movement about the pin 117. The opposite ends of the plates are held in proper lateral spaced relationship by pins 118 with the result that both plates 114 swing as a unit about the pin 117.

Supported between the plates 114 for sliding movement lengthwise of the latter is a jaw member 119 held in assembled relation to the plates 114 by a pair of plates 120 respectively secured to the top and bottom edges of the plates 114. A cooperating jaw member 121 is supported between the plates 114 by a pivot pin 122 for

swinging movement in a vertical plane. The jaw 121 is positioned rearwardly beyond the jaw 119 and cooperates with the latter to grip a vertical bar 123 therebetween. The lower end of the bar 123 is pivotally supported on the frame 22 by a pin 124, and cooperates with the gripping jaws in the position thereof shown in Figure 4 of the drawings to hold the beet topping mechanism 27 in its elevated position.

Referring again to Figures 3 and 4 of the drawings, it will be noted that the gripping jaw 119 is connected to the plates 114 by toggle linkage 125. The linkage 125 comprises a pair of links 126 having their adjacent ends pivotally connected together by a pin 127, and having their outer ends respectively pivotally connected to the jaw 119 and to the plates 114. The arrangement is such that when the toggle linkage 125 is in its extended position shown in Figure 4 of the drawings, the jaw 119 urges the bar 123 toward the jaw 121. The jaw 121 is normally swung upwardly into frictional contact with the bar 123 by a coil spring 128 having one end connected to the plates 114, and having the other end connected to the jaw 121 rearwardly beyond the pivot 122. In this connection attention is called to the fact that when the gripping jaws are in clamping engagement with the bar 123, the jaw 121 is inclined in a downward direction, as shown in Figure 4 of the drawings. Thus upward movement of the plates 114 or beet topping mechanism 27 relative to the bar is permitted, but downward movement of the plates 114 in relation to the bar 123 merely increases the gripping action, and is prevented.

The toggle 125 is operated by a vertical link 129 having the upper end pivoted to the pin 127 and having the lower end pivoted to the rear end of a link 130. The link 130 is pivoted intermediate the ends on the plates 69 by a pin 131, and the forward end of the link is positioned in the path of the pin 67, as clearly shown in Figures 3 and 4 of the drawings. In fact in Figure 3 of the drawings the front end of the link 130 actually rests on the top of the pin 67, so that upon initial upward movement of the follower 56, the pin 67 engages the link 130 and swings the latter in a clockwise direction about the pin 131. As a result of this swinging movement of the link 130, the link 129 is moved downwardly to extend or straighten the toggle linkage 125, and thereby operate the latch mechanism 113 to grip the bar 123. As previously described, continued upward movement of the follower 56 causes the pin 67 to engage the upper edges of the enlarged openings 68 in the plates 69 and thereby elevates or raises the beet topping mechanism 27. For reasons noted above, upward movement of the beet topping mechanism 27 is permitted, notwithstanding the fact that the bar 123 is gripped between the jaws 119 and 121 of the latch mechanism.

When the beet topping mechanism is raised by the follower 56 to the elevation determined by the beet engaged by the topping mechanism, any tendency for the beet topping mechanism to drop is positively prevented by the gripping action of the jaws on the bar 123. The beet topping mechanism 27 is maintained by the latch 113 in its elevated position until the top of the beet has been severed. The latch 113 is then released in a manner to be presently described, and the topping mechanism 27 drops by gravity to its lowermost position shown in Figure 3 of the drawings. However, when the weight of the beet topping

mechanism 27 is transferred to the latch mechanism 113 as is the case just prior to the cutting operation, there is a tendency for the beet topping mechanism to drop slightly. As a result of this slight downward movement of the beet topping mechanism 27, the plates 114 swing downwardly a corresponding distance about the point of contact of the cooperating jaws with the bar 123, and this movement is transmitted to the rod 105 to disengage the same from the pawl 97 and initiate the operation of the casting element 42. In detail it will be noted that the rear end of the rod 105 extends through an opening formed in an enlarged extension 132 of the pin 117, and a portion of the rod 105 intermediate the ends extends through an enlargement 132' at one end of a pin 134 extending through the plates 114 adjacent the front ends thereof. As shown in Figure 8 the pin 134 has an opening intermediate the ends for slidably receiving the upper end of a generally vertically extending pin 135. The lower end of the pin 135 is pivotally connected to the plates 69 by a pin 136 extending between the latter plates. Upward movement of the rod 105 relative to the pin 135 is resisted by a nut 137 threaded on the upper end of the pin 135, and downward movement of the rod is determined by an annular shoulder 138 formed on the pin 135. A coil spring 139 is provided on the pin 135 and normally urges the rod 105 against the nut 137. When in this position the front end of the rod 105 is located in blocking relationship to the pawl 97, and the nut 137 may be adjusted to insure accurately positioning the rod relative to the pawl.

It follows from the above that when the front ends of the plates 114 swing downwardly slightly about the pin 117, the rod 105 is moved in a corresponding direction against the action of the spring 139 until the pin 134 carrying the rod abuts the shoulder 138. When the rod is in its lowermost position determined by the shoulder 138, the front end of the latter is swung out of blocking engagement with the pawl 97, and the latter is moved by the spring 103 to establish a driving connection between the plate 96 and the tubular shaft 35. As a result the casting element 42 is rotated by the shaft 35 to throw the severed beet top to one side of the row.

Rotation of the tubular shaft 35 by the clutch 95 imparts a corresponding rotation to the cam 107, and the latter has the additional function of releasing the latch 113 in timed relation to rotation of the shaft 35. As shown in Figures 4 and 10, a projection 140 is formed on the cam 107 in a position to engage the inner end of a plunger 141 during each revolution of the tubular shaft 35. The plunger 141 is slidably mounted in a sleeve 142 carried by the arcuate plate 71, and the outer end of the plunger is connected to a rock arm 143. The rock arm 143 is pivoted on the plates 69 by a pin 144 and is connected to a vertical bar 145 intermediate the ends of the latter. The upper end of the bar 145 is located directly below the pivotally connected ends of the toggle links 126, and the lower end of the bar is shown in Figure 7 of the drawings as slidably supported on a pivot pin 147 extending between the plates 69. A collar 148 is secured to the lower end of the bar 145 below the pin 147, and a coil spring 149 is positioned between the collar 148 and the pivot 147. The purpose of the coil spring is to maintain the bar 145 in its inoperative or lowermost position with respect to the toggle links 126. The above construction is such that after one complete revolution of the casting element 42, the

cam projection 140 operates the rock arm 143 through the medium of the plunger 141 to raise the rod 145 against the action of the spring 149. As shown in Figure 7 of the drawings, upward movement of the rod 145 swings the toggle linkage 125 upwardly to the position shown in Figure 3 of the drawings and releases the latch 113. As a result of releasing the latch 113 the beet topping mechanism 27 drops by gravity to its lowermost position shown in Figure 3 of the drawings. As the plates 69 move downwardly with the beet topping mechanism 27, the spring 139 swings the forward end of the rod 105 upwardly to locate the front end thereof in blocking relationship to the pawl 97. When the rod 105 is in the above position, the arm 101 on the pawl engages the front end of the rod 105, and swings to the full line position shown in Figure 15 of the drawings, wherein the arm 99 is released from the adjacent pin 100 on the clutch plate 96. As a result the tubular shaft 35 and associated casting mechanism 42 are disconnected from the clutch plate 96. The rod 105 remains in its blocking position until the next cycle of operation.

It has been stated above that the elevation of the disc 28 during the cutting operation is determined by engagement of the follower 56 with the preceding beet in the row. In order to more accurately position the cutting disc 28 relative to the beets, provision is made herein for stripping the foliage off the top of the beets. As shown in Figures 1 to 5 inclusive of the drawings, a disc 150 formed of rubber, synthetic rubber or some equivalent resilient material is secured to a shaft 151, which in turn, is rotatably supported on the plate 24. A pulley 152 is secured to the shaft 151 adjacent the disc 150 and is connected to another pulley 153 by a belt 154. The pulley 153 is secured to the front end of the shaft 84, which as stated above is supported in the tubular housing 85. The diameter of the disc 150 is determined to contact the top portions of the beets in the manner indicated in Figure 2. As a result advancement of the apparatus along a row of beets causes the peripheral portion of the disc 150 to wipe across the top portions of the beets, and strip the foliage from the latter. To assist in this operation, suitable metal inserts 156 may be secured to the peripheral portion of the resilient disc.

Operation

Assuming that the parts of the apparatus are in their inoperative positions shown in Figure 1 of the drawings, and that it is desired to traverse a row of beets, the usual hydraulically actuated lifting arms (not shown) of the tractor 21 are operated to advance the link 80'. Forward movement of the link 80' operates the link 79 to swing the links 72 downwardly against the stop 74. The rod 76 moves downwardly with the rear ends of the links 72 and permits the parallelogram arrangement of linkage to lower the beet topping mechanism 27 as well as the follower 56 to the lowermost positions shown in Figure 3 of the drawings. The remaining parts of the apparatus also assume the relative positions shown in Figure 3, and the apparatus is in condition for advancement along a row of beets.

As the apparatus moves along a row of beets, the follower 56 engages the top portion of a beet and swings the rear ends of the links 62 upwardly about the pin 64. Upon initial upward movement of the links 62 the pin 67 engages the front end of the link 130 and swings the rear end of the link 130 downwardly to straighten

11

the toggle links 126, as shown in Figure 4 of the drawings. As a result of straightening the toggle linkage 126 the vertical bar 123 is gripped between the clamping jaws 119 and 121. Continued upward movement of the links 62 engages the pin 67 with the plates 69 and swings the parallelogram linkage upwardly to raise the cutting disc 28 a distance depending on the height of the beet engaged by the follower. The relative position of the follower 56 and cutting disc 28 is such that the disc severs the top portion of the beet as the follower travels beyond the beet. The disc 27 is retained in its elevated position throughout the cutting operation by the latch 113.

However, as the follower 56 moves beyond the top portion of an adjacent beet, the weight of the mechanism 27 is transferred to the latch 113. Inasmuch as the plates 114 carrying the latch gripping jaws cannot move downwardly relative to the bar 123, and since the plates 114 are pivoted to the plates 69 by the pin 117, it follows that the front end portions of the plates will move downwardly to engage the pin 134 with the shoulder 138 on the pin 135, shown in Figure 4 of the drawings. In view of the fact that the rod 105 slidably engages the pin 134, it also follows that the front end of the rod 105 swings downwardly out of blocking engagement with the pawl 97 permitting movement of the latter to the dotted line position thereof shown in Figure 15 of the drawings, wherein the arm 99 engages the adjacent pin 100 on the clutch plate 96 to impart a rotative movement to the tubular shaft 35. Thus the casting element 42 is rotated by the shaft 35 to throw the severed beet top to one side of the row.

As the tubular shaft 35 rotates, the cam projection 149 moves the rod 145 upwardly to release the latch 113, and thereby permit the beet toppling mechanism 27 to fall by gravity to its lowermost position shown in Figure 3 of the drawings. This downward movement of the beet toppling mechanism 27 returns the front end of the rod 105 to a position in the path of travel of the arm 101 on the pawl 97, and operates the pawl to release the clutch 95. As a result rotation of the casting element 42 is discontinued, and the apparatus is ready for the next cycle of operation. It is pointed out again that any tendency for the casting element 42 to rotate in a reverse direction by the reaction resulting from disconnecting the clutch 95 is prevented by engagement of the plunger 108 in Figure 11 of the drawings with the shoulder 112 on the cam 107.

What I claim as my invention is:

1. Beet harvesting apparatus comprising a frame movable along a row of beets, a supporting member mounted on the frame for movement in up and down directions relative to the frame, a shaft journaled on said member with its axis extending in an up and down direction and having the lower end spaced below the frame, a cutter mounted on the lower end portion of the shaft for rotation thereby, vertically spaced substantially parallel first and second arms having corresponding ends pivoted to the frame and having the opposite ends pivoted to the supporting member, the distance between the axes of the pivotal connections of the first arm being substantially the same as the distance between the axes of the pivotal connections of the second arm to permit raising and lowering of the cutter without changing the angular relationship of the shaft to the frame, a driving element supported on the frame for rotation, a driven element mounted on

12

the supporting member for rotation and connected to said shaft, the axes of said elements lying in a common plane parallel to the arms, and means operatively connecting said elements.

5 2. The beet harvesting apparatus defined in claim 1 comprising a third arm pivoted to the frame for swinging movement in a vertical direction and having the swinging end connected to the supporting member, and a beet engaging part positioned in advance of the cutter and connected to the swinging end of the third arm.

15 3. The beet harvesting apparatus defined in claim 2 comprising releasable latch means having cooperating engaging parts respectively mounted on the frame and supporting member for holding the supporting member in an elevated position relative to the frame, and means operated by the third arm for actuating said latch.

4. Beet harvesting apparatus comprising a

20 frame movable along a row of beets, a supporting member mounted on the frame for movement in up and down directions relative to the frame, a shaft journaled on said member with its axis extending in an up and down direction and having the lower end spaced below the frame, a cutter mounted on the lower end portion of the shaft for rotation thereby, vertically spaced substantially parallel first and second arms having corresponding ends pivoted to the frame and having the opposite ends pivoted to the supporting member, the distance between the axes of the pivotal connections of the first arm being substantially the same as the distance between the axes of the pivotal connections of the second arm to permit raising and lowering of the cutter without changing the angular relationship of the shaft to the frame, means supported by the frame in a position to successively engage beets in advance of the cutter for elevating said cutter, said elevating means

25 comprising a third arm pivoted to the frame for swinging movement in a vertical direction and connected to the supporting member, a beet engaging part connected to the swinging end portion of the third arm for operating the latter, and a releasable latch mechanism operated by the third arm for holding said cutter in the elevated position determined by the elevating means.

30 5. Beet harvesting apparatus comprising a frame movable along a row of beets, a supporting member mounted on the frame for movement in up and down directions relative to the frame, a shaft journaled on said member with its axis extending in an up and down direction and having the lower end spaced below the frame, a cutter

35 mounted on the lower end portion of the shaft for rotation thereby, vertically spaced substantially parallel first and second arms having corresponding ends pivoted to the frame and having the opposite ends pivoted to the supporting member, the distance between the axes of the pivotal connections of the first arm being substantially the same as the distance between the axes of the pivotal connections of the second arm to permit raising and lowering of the cutter without changing the angular relationship of the shaft to the frame, a third arm pivoted to the frame for swinging movement in an up and down direction, a lost motion pivotal connection between the swinging end portion of the third arm and supporting member permitting limited swinging

40 movement of the third arm relative to the supporting member, a beet engaging part connected to the swinging end portion of the third arm and positioned in advance of the cutter, releasable latch means having cooperating engaging parts

respectively mounted on the frame and supporting member for holding the supporting member in an elevated position, and means operated by the third arm as the latter swings upwardly relative to the supporting member for operating said latch means.

6. Beet harvesting apparatus comprising a frame movable along a row of beets, a supporting member mounted on the frame for movement in up and down directions relative to the frame, a shaft journaled on said member with its axis extending in an up and down direction and having the lower end spaced below the frame, a cutter mounted on the lower end portion of the shaft for rotation thereby, vertically spaced substantially parallel first and second arms having corresponding ends pivoted to the frame and having the opposite ends pivoted to the supporting member, the distance between the axes of the pivotal connections of the first arm being substantially the same as the distance between the axes of the pivotal connections of the second arm to permit raising and lowering of the cutter without changing the angular relationship of the shaft to the frame, a drive shaft journaled on the frame with its axis extending parallel to the pivot axes of the arms and having a sprocket secured thereto, a driven shaft journaled on the supporting member with its axis extending parallel to the axis of the drive shaft and positioned so that a common plane passing through the axes of the drive and driven shafts lies parallel to the arms, a sprocket fixed to the driven shaft, a chain connecting said sprockets, and means operatively connecting the driven shaft to the cutter shaft. 30

7. The best harvesting apparatus defined in claim 6 comprising means connected to the supporting member and positioned in advance of the

cutter for engagement with the tops of beets to elevate said cutter.

8. The beet harvesting apparatus defined in claim 7 having means operated by the elevating means for holding the cutter in the elevated position determined by said elevating means.

9. Beet harvesting apparatus comprising a frame movable over a row of beets, a supporting member mounted on the frame of movement in up and down directions relative to the frame, a shaft journaled on said member with its axis extending in an up and down direction and having the lower end spaced below the frame, a cutter mounted on the lower end of the shaft for rotation by said shaft, means connected to the supporting member and positioned in advance of the cutter for engagement with the tops of beets to elevate said cutter, and a stripper supported by the frame in advance of the elevating means and having means engageable with adjacent beets to remove the foliage from the tops of the beets. 15

10. The beet harvesting apparatus defined in claim 9 wherein the stripper comprises a disc supported on the frame for rotation about an axis extending in the direction of movement of the frame along a row of beets and having a flexible peripheral portion engageable with the beet tops, and means for rotating said disc. 20
